UNITED STATES PATENT OFFICE

2,425,576

SUCTION CLEANING DEVICE FOR SPINNING MACHINES AND THE LIKE

Meinard F. Thoma, Fitchburg, Mass.

Application June 23, 1944, Serial No. 541,807

2 Claims. (Cl. 19—139)

1

The present invention relates to an improved suction device for employment in connection with the drawing rolls of spinning frames and similar textile machinery, for collecting and removing broken ends, as well as for keeping the cylindrical roll surfaces free from any accumulation of fly, lint and other waste material.

Suction devices for collecting and removing broken ends from spinning machinery, as heretofore constructed, have comprised suction heads extending in proximity to the drawing rolls, with each head providing a series of spaced suction openings arranged to coincide with the spacing of the individual rovings. Such a prior device is shown, for example, in the copending application of Heinrich Thoma, Serial No. 414,796, filed October 13, 1941, for Exhaust plant for spinning machines for catching and removing thread ends, since issued as Patent No. 2,354,893 on August 1, 1944.

According to the present invention, there is provided an improved suction device of the above described general construction, which device is characterized by the employment of suction heads so constructed as to be capable of performing the dual function of removing loose ends, as well as keeping clean the adjacent roll surfaces from any accumulation of fly, lint, or other waste material.

The above and other advantageous features of the invention will hereinafter more fully appear from the following description, considered in connection with the accompanying drawings, in which—

Fig. 1 is a diagrammatic view, partially in section, showing the installation of a suction device embodying the invention in association with a spinning machine.

Fig. 2 is a view in front elevation of a portion of the drawing roll section of the spinning frame shown in Fig. 1, on an enlarged scale.

Fig. 3 is a vertical sectional view along the line 3—3 of Fig. 2, looking in the direction of the arrows.

Fig. 4 is a plan view of an individual suction head and its associated conduit, such as is shown in Fig. 2.

Referring first to Fig. 1, there is shown a portion of a spinning frame providing spools 1, from which roving 2 is drawn by rolls 3 for winding on spindles 4 in a manner usual with the operation of spinning machinery. In accordance with the present invention, there is incorporated in the spinning frame a conduit 5 extending longitudinally of the machine, this conduit being

readily built into the existing machine below the creel spool stand 6. The conduit 5 has a rectangular cross section, with one end closed as indicated in Fig. 4, and its opposite open end connected to a suitable suction source as indicated by the arrows at 7.

The conduit 5 provides a series of suction heads 8 projecting from opposite sides thereof, with the several heads of each series extending along the machine transversely to the rovings 2, as the latter move downwardly from the drawing rolls 3 to the spindles 4, as indicated in Fig. 1. As best shown in Figs. 2 and 3, each suction head 8 provides a continuous slot 9 constructed in such a manner as to not only collect and remove broken ends of rovings, but also to prevent the accumulation of fly and lint on the associated drawing rolls 3. It is to be noted in Fig. 2 that the front drawing roll 3 provides the usual fluted portions 10 separated by smooth portions 11 of smaller diameter, and the suction slot 9 of each head 8 is formed with end collecting portions 12 and cleaning portions 13 corresponding in length to the above described roll portions 10 and 11, respectively.

Referring now to Fig. 3, it will be seen that the end collecting portion 12 of each suction slot 9 is located forward of the axis of the front drawing roll 3 just below the fluted portion 10, so that any broken ends of roving 2 will be drawn into the suction head, as indicated by the dotted arrow. Furthermore, it is apparent that the cleaning portion 13 is disposed so that it is close to the smooth portion 11 of the roll 3 where it will function to remove any fly, lint, or other waste material from this portion of the roll, as indicated by the dotted arrow.

It will also be apparent from a consideration of Fig. 4 that each suction head 8, as viewed in plan, will show the slot 9 as a continuous alternating line, with the lengths of the end collecting portions 12 and cleaning portions 13 corresponding to the lengths of the fluted portions 10 and smooth portions 11 of the particular front roll 3 with which the head may be employed. Therefore, each suction head performs a dual function, namely to collect and remove any broken ends from the associated drawing rolls and to continuously exert a cleaning action on the smooth roll surfaces between the fluted portions. Obviously, a cleaning action is also performed by the end collecting slot portions 12, with respect to any fly or lint on the fluted roll portions 10.

55 From the foregoing, it follows that by the pres-

ent invention there is provided an improved suction cleaning device for spinning machines and the like, whereby loose ends of roving will be effectively gathered and removed, along with any waste material such as fly and lint resulting from the spinning operation.

I claim:

1. A device for collecting and removing broken ends in machines for performing a textile operation on roving, comprising in combination cooperating rolls for passing roving therebetween, a suction element extending longitudinally of the rolls, said element being connected to a source of suction at one end and closed at its other and providing a continuous longitudinally extending slot of irregular form having portions extending parallel to the roll surfaces for collecting and removing broken ends from the rolls, and other portions offset with respect to said first named slot portions for removing loose fly, lint and other waste material resulting from the textile operation.

2. A device for collecting and removing broken ends in spinning and like machines, comprising in combination cooperating pairs of rolls, certain of which provide alternate fluted and smooth portions of different diameters, a suction element extending longitudinally of the rolls, said element

being connected to a source of suction at one end and closed at its other and providing a continuous longitudinally extending slot having different portions thereof at different distances from the roll axis and of different lengths corresponding to said fluted and smooth portions for collecting and removing broken ends from the fluted portions of said rolls as well as loose fly, lint and other waste material resulting from the textile 10 operation from the smooth portions of said rolls.
